United States Patent Office.

WILLIAM E. BARTON, OF EAST HAMPTON, CONNECTICUT.

Letters Patent No. 104,690, dated June 28, 1870.

IMPROVEMENT IN SLEIGH-BELLS.

The Schedule referred to in these Letters Patent and making part of the same

I, WILLIAM E. BARTON, of East Hampton, in the county of Middlesex, Connecticut, have invented certain new and useful Improvements in Sleigh-Bells, of which the following is a specification.

Nature and Objects of the Invention.

My invention consists in a peculiar construction of sleigh-bells, primarily designed to adapt them to be smoothed and finished up in a lathe, and to be readily repolished in the same manner.

Description of the Accompanying Drawings.

Figure 1 is a plan view of two improved bells attached to the strap.

Figure 2 is an under-side view of one of the same, detached.

Figure 3 is a transverse vertical section of a single bell and its strap.

Figures 4 and 5 represent a common form of bell, fig. 4 being a plan view, and fig. 5 an under-side view of the same.

General Description.

I cast my improved bells *a* without a throat, supporting that part of the cone, which would otherwise be supported thereat, by projections formed by eyes *c* in the front hemisphere, or, in other words, I cast the bell with eyes, *b c*, in both hemispheres, and without a throat.

The eyes do not interfere with the operation of the chisel or flat turning-tool in turning, as the throat would.

The bell, as taken from the mold, is chuck'd in a lathe in ordinary manner, and finished up with a flat turning-tool and burnishing-tool, and, when finished, a fine saw is used to divide one hemisphere with a saw-cut, *e*, making a practical division sufficient for vibration in the front of the bell, and avoiding the unsightly appearance of the ordinary wide slotted throat shown in fig. 4.

To facilitate and extend the scope of turning, I cast a small nub or projection on the front of the bell, in the axial line of the same, and cast or otherwise make a drill center, *d*, therein, so that the bell may be supported by lathe-centers on both sides, while the finishing is done, and at any time afterward when the bells require refinishing or burnishing.

The nub *d* forms a part of the design or figure of the acorn-shaped bell. It may be left out of the globular bell, if so desired, and the center formed in the bell itself.

The saw-cut slot or throat *e* may be through the center *d*, or near it, as shown in fig. 1.

Claim.

I claim as my invention—

As a new article of manufacture, the improved sleigh-bell herein described, having a permanent lathe-center, *d*, and a saw-kerf throat or slit, *e*, for the purposes set forth.

W. E. BARTON.
